CLAIM

The ornamental design for a tire, as shown and described.

DESCRIPTION

FIG. 1 is a perspective view of a tire showing an embodiment of my new tread design, it being understood that the tread pattern is repeated uniformly throughout the circumference of the tire as shown schematically by solid lines and the opposite side is the same as that shown;

FIG. 2 is an enlarged fragmentary plan view of the embodiment of FIG. 1; and,

FIG. 3 is an enlarged fragmentary plan view of a second embodiment of my tire, it being understood that the tire is a mirror image of the tire shown in FIGS. 1-2.
